UNITED STATES PATENT OFFICE.

TYCHO VAN ALLER, OF SCHENECTADY, NEW YORK, ASSIGNOR TO GENERAL ELECTRIC COMPANY, A CORPORATION OF NEW YORK.

ELECTRIC HEATING UNIT.

No. 848,939.

Specification of Letters Patent.

Patented April 2, 1907.

Application filed December 29, 1905. Serial No. 293,746.

To all whom it may concern:

Be it known that I, TYCHO VAN ALLER, a subject of the King of Denmark, residing at Schenectady, county of Schenectady, State of New York, have invented certain new and useful Improvements in Electric Heating Units, of which the following is a specification.

This invention relates to electric heaters, and has for its object the provision of a device of this character which can quickly be brought up to the required temperature, is simple and cheap in construction, and at the same time durable, safe, and efficient.

My invention relates more specifically to heating devices to be used in connection with cigar-lighters, and while I do not limit my invention to this particular application nor to the particular type of cigar-lighter I have found that it adapts itself very conveniently for use in connection with the type of cigar-lighter shown and described in application of Julius Tournier, Serial No. 280,104, filed September 25, 1905. In this type of cigar-lighter a socket is provided which is adapted to receive a plug of substantially the same character as that of an incandescent-lamp socket and plug. The lighter is provided with a handle and push-button adjacent thereto, so that by operating the push-button a circuit is closed through the heater-plug.

It is the object of my invention, therefore, to provide an improved heater of this character; and my invention may be said to consist in the features of construction and the arrangement and combination of elements set forth, and particularly pointed out in the claims annexed hereto.

In the drawings, Figure 1 is a sectional view of a device embodying my invention. Fig. 2 is a sectional view on the line 2-2, Fig. 1, with the resistance-coils removed. Fig. 3 is a plan view of the device. Fig. 4 is a view similar to that of Fig. 2 with the resistance-coils in place, and Fig. 5 is a view of the resistance-coils.

Referring to the drawings, 1 is a base or plug, preferably of porcelain, and may be of the type in common use in incandescent lamps. The metallic threaded portion 2, adapted to screw into the lamp-socket, forms one of the terminals, while the metallic tip 3 forms the other. The plug is formed with an enlarged head and is cored out, as shown,

so as to admit the resistance-coils 4. This 55 resistance is from a continuous resistance-conductor, preferably of a nickel-steel-wire of sufficiently small section to permit direct connection across an incandescent-lamp circuit and wound into a series of parallel coils. 60 The plug is provided with the ledge 5, adapted to support the ends of the coils which abut against the stepped portion 5', thereby holding the coils firmly in place. The coils are thus supported at their ends, which will prevent the overheating of the other parts of the plug. One of the ends of the resistance-wire is connected with the screwed portion 2, and the other end is brought down through the center of the plug and cemented therein to 65 connect with the tip 3, as shown at 6. It has been found that in arranging coils as herein shown the outer ones, which do not receive so much heat from the other coils, cool off more quickly, and to overcome this objection I 70 wind these outer coils 7 and 8 so that the turns are closer together, thereby affording a higher resistance and bringing the temperature up to the point necessary to get an even distribution of heat. In the arrangement 75 shown the coils are placed close together and separated from each other by spacing-strips 9, preferably of mica. These strips also have their ends supported on the ledge 5 and are substantially the same in width as the coils 4 80 are in diameter. The strips and coils are held in place in any desired manner, as by means of cement 9', which also operates to secure the ends of the coils to the base, so as to prevent their contraction. The strips are 85 thus substantially flush with the top of the coils, so as to afford a support for the disk or shield 10. This shield is of a material which readily transmits the heat from the resistance-coils, preferably mica, and is firmly 90 supported around its outer edge by the porcelain and over the remaining portion of the surface by the spacing-strips. The shield may also rest upon the coils, if desired. The shield and coils are held in place by means of 95 a cap 11, preferably of metal and secured to the side of the plug in any desired manner. The cap projects over the shield for some distance, and is cut away at the center, so as to afford access to the shield. 100

In order to prevent the undue heating of the cap, I have so formed it that it is entirely out of contact with the mica shield except 105

around the edge of the central opening, as at 12. The edge of this opening is beveled down into contact with the shield and in addition to securing the latter in place prevents 5 the cigar-ashes and tobacco from working its way down under the shield and into the coils. This cap may be secured to the plug in such a manner as to be easily removable—as, for example, by means of the projecting lugs 13. 10 It will thus be seen that I have provided a cigar - lighter - heating plug which is well adapted for efficient and durable service. The mica strips in addition to spacing the coils form a firm support for the mica shield, 15 the life of which is thereby increased, since it is not subject to bending nor to being excessively heated in spots. The form of unit, moreover, which I have shown is found to be very efficient and durable in addition to being exceedingly cheap, while my improved 20 form of cap holds the parts in place, while itself having very slight contact-surface to cause heating thereof.

What I claim as new, and desire to secure 25 by Letters Patent of the United States, is—

1. An electric heating unit comprising an insulating-base, a series of resistance-coils having their ends supported in said base, similarly-supported insulating spacing-strips 30 between said coils, and a shield for said coils adapted to be supported by said strips.

2. An electric heating unit comprising an insulating - plug, a resistance - conductor wound into a series of coils and having only 35 their ends supported in said plug, a shield for said coils, and a retaining-cap for said shield secured to said plug and having a central opening, said cap being raised away from said shield and beveled around the opening 40 so as to form a bearing edge in contact with said shield.

3. An electric heating unit comprising an insulating - plug, a resistance - conductor wound into a series of coils arranged in a 45 plane and having their ends supported in said plug, similarly-supported insulating spacing-strips between said coils, a mica shield for said coils adapted to be supported by said strips, and a retaining-cap for said shield secured to said plug and having a central opening, said cap being raised away from said shield but having the edge of the opening bearing thereon.

4. An electric heating unit comprising an 55 insulating-base, a resistance-conductor wound into a series of parallel coils arranged in a plane and having their ends supported in said base, the turns of the outer coils of the series being closer together than those of the 60 inner coils.

5. An electric heating unit comprising an

insulating-plug, a resistance-conductor wound into a series of parallel coils arranged in a plane and having their ends supported in said base, the turns of the outer coils of the series being closer together than those of the inner coils, a mica shield for said coils, and means for securing 65 said shield to said plug.

6. An electric heating unit comprising an insulating-plug, a resistance-conductor wound 70 into a series of parallel coils arranged in a plane and having their ends supported in said base, the turns of the outer coils of the series being closer together than those of the inner coils, a mica shield for said coils, and insulating 75 spacing-strips between the coils and adapted to support said shield.

7. An electric heating unit comprising a porcelain plug, a resistance-conductor wound 80 into a series of parallel coils arranged in a plane and having their ends supported in said plug, the turns of the outer coils of the series being closer together than those of the inner coils, similarly-supported insulating spacing- 85 strips between said coils, a mica shield for 90 said coils adapted to be supported by said strips, and a retaining-cap for said shield secured to said plug and having a central opening, said cap being raised away from said shield but having the edge of the opening 9 bearing thereon.

8. An electric cigar-lighter comprising a plug for an incandescent-lamp socket having a threaded stem to enter a socket, a refractory insulating-support, a continuous coil of 95 reflexed resistance-wire supported at intervals therein, refractory insulating spacing-strips between the several reflexes, and a cap containing an opening to admit a cigar or the like.

9. An electric heating unit comprising an insulating-base, a series of resistance-coils having their ends supported therein, insulating-strips between said coils, and a shield for 100 said coils adapted to be supported by the strips.

10. An electric heating unit comprising an insulating-plug, a resistance-conductor wound into a series of coils arranged in the base, and having their ends supported in said plug, insulating spacing-strips between said coils, a mica shield for said coils, adapted to be supported by the strips, and a retaining-cap for the shield secured to the plug and having a central opening.

In witness whereof I have hereunto set my hand this 26th day of December, 1905.

TYCHO VAN ALLER.
